UNITED STATES PATENT OFFICE.

EDGAR A. BEEBE, OF DOWNEY, IDAHO.

AUTOMATIC SWITCH.

Application filed August 1, 1921. Serial No. 489,032.

This invention relates to charging systems for storage batteries, and particularly to systems which prevent complete discharge of the batteries before the recharging commences.

One object of the invention is to provide a switch which is associated with an ampere-hour meter, and by means of which the operation of recharging is begun before the battery can become fully discharged.

Another object is to provide a switch of this character which is operated automatically by the ampere-hour meter.

Other objects and advantages of the invention will be understood from the following description.

In the drawings:

Figure 1 is a view showing a storage battery, ampere hour meter and automatic cut out represented diagrammatically in proper correlation with a load to effect the object of the present invention.

Figure 2 is an enlarged plan view of the ampere-hour meter.

Figure 3 is a side elevation of the meter, a portion of which is broken away.

Referring now to the drawings there is shown at 10 a storage battery having the usual terminals 11 and 12.

In connection with the storage battery is illustrated diagrammatically a load represented by a series of lamps 13 in multiple between the load circuit wires 14 and 15 of which the latter leads to the battery terminal 12 through the automatic cut out which will be later described.

The load circuit wire 15 leads to the switch arm 16 of an automatic electric cut out, to be presently more particularly described and the terminal contact plate 17 of which is movable with the arm into and out of contact with a fixed contact plate 18. The contact 18 is connected by a wire 19 with one terminal of an ampere hour meter 20 to be presently more particularly explained and from the other terminal of which leads a wire 21 to the terminal 12 of the storage battery. With this arrangement it will be understood that so long as the plates 17 and 18 are in mutual contact, the load will be in circuit with the storage battery, and that when the arm 16 moves to carry its contact plate 17 from engagement with the contact plate 18, the circuit with the storage battery will be broken.

Through the medium of a circuit closer actuated by the ampere hour meter, there is closed a shunt circuit across the load, and which shunt circuit includes the actuating electro-magnet of the cut-out. Of these mechanisms the automatic cut out will be first described in construction and operation.

The automatic cut-out includes an electro-magnet 48, having the pivoted armature 36, provided with the hooked end for engagement with the rocker 32. A flexible metallic contact arm 16 is mounted for engagement by the roller 34, of one end of the rocker 32, and has a contact tip 17 on its free end for engagement with a stationary contact 18. The wire 15, of the load circuit 13 is connected with the fixed end of the flexible arm 16, as shown at 25, while the ends of the coil of the electromagnet 48 are connected respectively to the binding posts 25 and 56, said wires being indicated at 55 and 59, respectively. A wire 60 is also connected with the post 25, and is connected with the switch which will be more particularly described later herein, in connection with the ampere-hour meter.

To effect energization of the electro-magnet when the battery charge has dropped to a predetermined condition, there is placed in circuit between the contact plate 18 and the terminal 12 of the storage battery, the ampere hour meter 20 that includes a hand 53 that traverses a dial 73, the hand serving to effect closure of the shunt circuit across the load and in this shunt circuit the winding of the electromagnet 48 is included. For this purpose, one terminal of the electro-magnet 48 is connected by means of a wire 60 with the before-mentioned binding screw 25, thus connecting one terminal of the magnet winding with one side of the load through the load circuit wire 15. The other terminal of the electro-magnet winding is connected by a wire 59 to the screw 56, which screw is passed through the insulating plate 22 and through the bushing 57, in the base plate 23, that is provided with a binding nut 58 for retaining one end of the wire 60, the other end of said wire 60 being connected with a spring contact finger 61 mounted on an insulating base 62 that is in turn carried by a ring 63 that is rotatably mounted on the meter hand 53, coaxial to the meter hand 53 so that this insulating base may be angularly adjusted about the 110

axis of the meter hand, for a purpose to be presently explained. Pivoted upon the insulating base 62 is an insulating block 64 from one end of which extends a switch contact arm 65 against which the spring contact finger 61 bears in electrical contact with it, the finger 61 serving to urge the contact head 66 of the contact arm against a contact plate 67 that is fixed upon the base 62. The contact plate 67 is connected by a wire 68 with the load circuit wire 14, in the diagram, and thence to the battery terminal 11. Thus it will be seen, that when the switch arm 65 engages the contact 67, the shunt circuit is closed through the electro-magnet, which is energized to move the latch to its inoperative position and release the switch arm 16, when the contact 17 moves from the contact 18 and both the latch circuit and the shunt circuit are broken.

In order that the closing of the shunt circuit may be controlled by the position of the meter arm 53, the spindle 69 of the meter that carries the arm, has a radial recess 70 and upon the periphery of this spindle, outwardly of the arm 53 there bears the laterally directed free end 71 of the finger 72 that is carried also by the insulating block 64 and extends therefrom in the opposite direction from the contact arm 65. So long as the extremity 71 of the finger 72 is upon the cylindrical periphery of the spindle 69, the lever 65 is held with its head 66 out of contact with the plate 67. Whenever the spindle moves to a position to receive the portion 71 within the radial recess 70, the lever 65 will be permitted to swing to engage its head 66 with the contact plate 67 under the influence of the spring finger 61, which will be readily understood.

The ampere hour meter includes a dial 73

that is numbered with graduations to indicate charge conditions in the battery and by shifting the base 62 angularly of the spindle axis, so that the pointer 74 may indicate the desired number on the dial, the mechanism will operate to close the shunt circuit and effect operation of the cut out when the charge condition of the battery corresponds.

When the battery is again to be recharged, the operator raises the arm 72 from the notch 70, and rotates the hand back to zero, or some other point near zero, corresponding to the amount of the current in the battery. The angular end 71 of the arm will then rest on the peripheral face of the spindle or arbor of the hand.

What is claimed is:

The combination with, of an ampere-hour meter including a dial and a hand for traversing dial, the hand having a notch in its arbor, of a ring adjustable circularly around the dial of the meter and having a mark arranged to be disposed opposite one of the indicating marks of the dial, a support carried by and extending radially from the ring and movable therewith, a pair of contacts mounted on the support, one of the contacts being flexible, and an insulated rocker mounted on the support, a flexible arm carried by and extending from one end of the rocker, said arm having one end engaging the arbor and terminally formed with a projection arranged to enter said notch upon the hand reaching a predetermined point on the dial, and a contact finger extending from the other end of the rocker between said pair of contacts, and normally urged by the flexible contact toward the other contact.

In testimony whereof, I affix my signature.

EDGAR A. BEEBE.
